United States Patent

Des. 235,340
Patented June 10, 1975

235,340

STORAGE BIN OR SIMILAR ARTICLE

Erbie Gail Mize, Chattanooga, Tenn., assignor to
Astec Industries, Inc., Chattanooga, Tenn.

Filed Nov. 19, 1973, Ser. No. 417,479

Term of patent 14 years

Int. Cl. D25—99

U.S. Cl. D23—2

FIG. 1

FIG. 1 is an isometric view of the storage bin; and
FIG. 2 is a side elevation view of the storage bin, as
viewed from the right of FIG. 1.

The storage bin as viewed from the left of FIG. 1, from
the back of FIG. 1, and from the front of FIG. 1, is iden-
tical to FIG. 2.

I claim:

The ornamental design for a storage bin or similar arti-
cle, as shown and described.

FIG. 2
